(57) **CLAIM**

The ornamental design for a combined torchiere lamp and
adjustable accent lights, as shown and described.

DESCRIPTION

FIG. 1 is a full front elevational view thereof;
FIG. 2 is an enlarged fragmentary perspective view, for
clarity of illustration;
FIG. 3 is a front elevational view of FIG. 2;
FIG. 4 is a right side view of FIG. 2;
FIG. 5 is a left side view of FIG. 2;
FIG. 6 is a topplan view of FIG. 2; and,
FIG. 7 is a bottom plan view of FIG. 2.
The broken lines shown in the drawing are environmental
only and form no part of the claimed design.
